UNITED STATES PATENT OFFICE

2,667,880

COIN CHANGING MECHANISM

Spencer L. Childers, Fresno, and William B. Warren, Madera, Calif., assignors to Vendorlator Manufacturing Company, Fresno, Calif., a corporation of California

Application February 11, 1952, Serial No. 271,026

6 Claims. (Cl. 133—2)

1

The present invention relates to coin handling devices and more particularly to improvements in coin-changing mechanisms directed to the minimizing of coin jamming therein and conducive to the smooth trouble-free handling of change-making coins.

Although the principles of the change-making mechanisms of the present invention are applicable to various types of coin handling devices, they were developed in conjunction with the "Coin Changer" comprising the subject matter of United States patent application Serial No. 216,236, filed March 17, 1951, by Spencer L. Childers, William B. Warren and Thomas K. Algor, as co-inventors, and now abandoned. For descriptive convenience, frequent reference is made herein to the coin changer of the specified application which, for brevity, is designated the "parent changer."

It is sufficient at this point to observe that the parent changer utilizes a coin drum mounted for rotation about a substantially horizontal axis. The drum is formed with a plurality of axially adjacent coin compartments adapted to receive coins of predetermined denomination therein in individual planes normal to the axis of rotation and with peripheral edges of the coins peripherally extended from the drum. The edges of the coins serve certain unlatching functions upon drum rotation with which the instant invention is not particularly concerned. In rotating the drum it is successively located in a coin receiving position with the compartments upwardly disposed and a coin discharging position with the compartments downwardly disposed.

Upwardly of the drum, the parent changer is provided with a coin detector which serves to reject spurious objects and all but coins of predetermined denominations and to segregate the accepted coins into individual denominations for delivery to their respective compartments in the drum.

To preclude premature cascading of the coins from the drum of the parent changer, an arcuate coin directing member or trough, is extended from a position laterally adjacent to the drum, in the direction of drum rotation from the top thereof, to a position below the drum. All coins except the lowest denomination are directed into a coin accumulating hopper provided therefor. The coin directing member provides a channel aligned with the coin compartment for the lowest denomination coins which is longitudinally slotted directly below the drum for the passage of the lowest denomination coins therethrough. A coin

2

tube is mounted directly below the slotted portion of the coin directing member to receive the coins of the lowest denomination for change-making purposes. To direct excess coins of the lowest denomination from the top of the tube when the tube is full, an extension of the coin directing member is directed downwardly from the top of the tube to the hopper.

It has been found that in the operation of the parent changer coins of the lowest denomination sometimes become jammed on edge between the drum and the coin tube, between the drum and the uppermost coin of a stack thereof in the tube, side by side within the slot, and between the drum and the extension of the coin directing means. Further, the parent changer makes provision for the optional employment of a coin compartment for the coins of a lowest denomination of sufficient size to accommodate a pair of such coins. It has even been found that the pair of coins occasionally jam in diametric alignment in several of the positions described above. Although such jamming is not frequent, its even occasional occurrence is intolerable in coin controlled vending machines and the like in which continuous trouble-free functioning is essential to profitable operation.

It is an object of the present invention, therefore, to provide an improved coin-changing mechanism minimizing coin jamming tendencies.

Another object is to provide an improved coin directing member and change accumulating coin tube in a coin changer of the character described.

Another object is to minimize or obviate the jamming of coins as they are fed to, or traveled over, coin accumulating reservoirs in coin changers.

Further objects and advantages will become apparent in the subsequent description in the specification.

In the drawing:

Fig. 1 is a fragmentary front elevation of a coin changer of the designated parent type modified to incorporate the principles of the present invention.

Fig. 2 is a section taken on line 2—2 of Fig. 1.

Fig. 3 is a sectional view of the coin-changing mechanism, as taken on line 3—3 of Fig. 2, but showing certain elements thereof in a successive operational position as subsequently more fully described.

Fig. 4 is a sectional view similar to Fig. 3 but showing certain elements thereof in a further advanced position.

Fig. 5 is a section taken on line 5—5 of Fig. 1. Referring in greater detail to the drawing:

As shown in the copending patent application identified above but not shown in the instant application, the parent coin changer is frequently applied to vending machines having an insulated cabinet in which articles to be vended are stored in a chilled condition prior to vending. The insulated cabinet provides a door 10, fragmentarily illustrated in the accompanying drawing, having a rear wall 11 and a forward wall 12.

A sheet metal mounting box 17 is located between the rear wall 11 and the front wall 12 of the door 10 having a back wall 18 and a floor 19 with its back wall 18 secured to the rear wall 11 of the door to support the box within the door. A bearing plate 20 transversely spans the front of the mounting box, partially enclosing it.

It will be noted that the parent coin changer, previously briefly described, modified to embody the teachings of the subject invention, is mounted with the box 17. A shaft 22 is rotatably mounted in a substantially horizontal position between the back wall 18 and the bearing plate 20 and is provided with a handle 23 by which the shaft is rotatable in a clockwise direction, as viewed in Figs. 1, 3, and 4.

A cylindrical coin drum 25 is rigidly mounted concentrically on the shaft 22 and provides a plurality of coin compartments 26, 27, and 28 therein. The compartments are adapted to receive coins of predetermined individual denominations, such as nickels, dimes, and quarters, respectively, therein in planes normal to the shaft 22 and with coins therein edgewardly extended from the periphery of the drum. As evident in Figs. 3 and 4, the nickel compartment 26 is formed to receive a pair of nickels 29 and 30. The inner nickel 29 may be made captive as by a pin 31 to reduce the capacity of the compartment to a single transient nickel 30 peripherally extended from the drum. By removal of the pin, both of the nickels are transient in nature as required in the vending of articles costing a dime and requiring two nickels, a dime, or a quarter for vending purposes. For articles costing a nickel, the pin 31 is utilized to retain the captive nickel 29 and the coin changer operates to render appropriate change for dimes and quarters.

The shaft 22 is illustrated as mounting a driving cog 33 usually coupled to a vending mechanism, and a ratchet wheel 34. Also shown in the drawing, is a ratchet pawl 35 engaged with the wheel 34 to limit shaft rotation to clockwise progression as viewed in Figs. 1, 3, and 4 and a plurality of change making levers 36 coupled to a change delivering slide mechanism 37 in a manner shown and described in the above identified patent application. A lever is aligned with the dime compartment 27 and another lever with the quarter compartment 28 so that when change is required for a dime, the dime lever is operated by dime engagement as the drum is rotated, and so that when change is required for a quarter the quarter lever is operated by quarter engagement as the drum is rotated.

A funnel member 40 is mounted in the box 17 above the drum 25 and provides passages therethrough individually vertically aligned with the compartments 26, 27, and 28 when the drum is in coin-receiving position.

An arcuate coin-directing member 41 is mounted on the back wall 18 and extended from a position laterally adjacent to the drum concentri-

cally of the drum in the direction of rotation of the drum to a position directly beneath the drum and thence downwardly transversely beneath the drum, as evident in Figs. 3 and 4. The directing member 41 has channels 43, 44, and 45 therein individually aligned with the paths of movement of the nickel compartment 26, dime compartment 27, and quarter compartment 28, respectively, incident to drum rotation. A substantially cylindrical hollow coin-collecting tube 48 is vertically mounted directly below the drum on the change-delivering slide mechanism 37 and serves to supply change-making coins to said mechanism. A locking pawl 38 is extended transversely of the change-making levers 36 and is so associated with the drum 25 that until a lever is raised to release the pawl, rotation of the drum beyond a predetermined point is precluded thereby. An extension 49 of the coin-directing member 41 is extended downwardly from the coin-directing member to a coin-accumulating hopper, not shown. Not only is the coin-directing member 41 mounted on the back wall 18 but for further dependable support, a plate 50 is mounted in the box 17 in spaced relation to the back wall forwardly adjacent to the coin-directing member and supports said members by means of screw-threaded bolts 51 extended therethrough.

The structure described to this point is essentially as shown and described in greater detail in the above identified patent application. The present invention is concerned with modifications in the coin-directing member 41, and coin tube 48, and additions thereto.

As the shaft 22 is rotated in the parent changer, any dimes and quarters received by the drum 25 are directed by the channels 44 and 45 to the extension 49 for gravitational discharge down the extension. Any transient nickels received by the nickel compartment 26 are guided by the nickel channel 43 as the drum is rotated and are dropped into the tube 48 until the tube is filled subsequent to which they are directed across the uppermost coin in the tube and gravitationally descend the extension. The jamming in the parent changer occurs in the dropping of the nickels into the tube or in moving them thereacross for descent on the extension.

Attention is now directed to the specific improvements made by the present invention which serve to eliminate the jamming.

As evident in Figs. 2, 3, and 4, the nickel channel 43 is slotted, as at 52, for descent of nickels therethrough into the tube 48 but in a different position than in the parent changer. The coin-directing member 41 is mounted so that the nickel channel 43 extends transversely diametrically across the upper end of the coin tube 48. In the parent changer, the nickel channel was slotted from a position in advance of the coin tube transversely thereacross. It has been discovered that a source of jamming is eliminated if the nickel channel 43 is slotted from a position inwardly adjacent to the side of the coin tube 48 from which coins approach the tube during drum rotation, as indicated at 53, diametrically transversely of the tube and downwardly beyond the tube to a position soon to be described in greater detail. Further, an additional source of jamming is obviated by slotting the tube 48 downwardly from the upper end thereof at the side opposite that from which coins approach the tube and in alignment with the slot

52. The inner diameter of the coin tube is preferably substantially equal to the diameter of the nickels or other coins to be received therein. The slot 55 is preferably approximately as long as the diameter of the nickel, or other coin, to be received in the tube. By terminating the slot 52 at its upper end 53 at a position intermediate vertical alignment with the center of the tube and the forward side thereof, superior operation is attained. This assures that the nickels will roll in their channel 43 upon drum rotation until their centers have passed vertical alignment with the center of the tube before they descend through the slot 52 and thus, to get into the tube, must gravitate downwardly and backwardly relative to their rolling movement in the channel. As evident in Figs. 3 and 4, the slot 55 accommodates the return movement of the nickel into the tube.

The lower end of the tube slot 55 and the lower end of the slot 52 in the coin-directing member 41 are preferably at substantially the same elevation, as evident in Figs. 3 and 4, and spaced a distance less than the diameter of the tube 48. A headed pin 60 is screw-threadably mounted in the plate 59 in a downwardly disposed position laterally adjacent to the slot 52. A helical spring 61 is mounted on the pin and has a leg 62 attached to the plate and a resilient leg 63 extended transversely of the slot 52 at a position vertically aligned with a position intermediate the lower ends of the slots 52 and 55. The leg 63 is spaced from the lower end of the slot 55 a distance less than the diameter of the tube and is spaced from the upper end 53 of the slot 52 a distance approximating but more than the diameter of the tube.

As a convenience in mounting the coin-directing member 41 with the slot 52 thereof in the precise diametric relation to the tube 48 desired, a shorter slot 56 is formed downwardly from the upper end of the tube 48 in diametric relation to the longer slot 52. A boss 57 is provided on the coin-directing member 41 in alignment with the slot 52 and is fitted downwardly into the shorter slot. The engagement of the boss in the shorter slot is not only an assembling convenience but assures the maintenance of proper relation between the directing member and the tube during extensive operation.

Operation

The operation of the present invention is believed to be clearly apparent and is briefly summarized at this point. Acceptable coins, such as nickels, dimes, and quarters, are delivered to the funnel member 40 by a coin rejector, not shown. If the coin-change mechanism is conditioned for nickel operation, the location of a nickel in the nickel compartment 26, of a dime in the dime compartment 27, or a quarter in the quarter compartment 28 is adequate to release the mechanism for operation by rotation of the handle 23 and to render change for the dime or quarter.

A dime or a quarter carried by its respective compartment in the drum 25 during rotation lifts its corresponding change-making lever 36, withdrawing the locking pawl 38 and releasing appropriate change therefor as described in the above identified copending patent application. As the drum is rotated, the dime or nickel is rolled down its respective channel 44 and 45 and descends the extension 49 into a hopper, not shown, provided for coin collecting purposes.

When the drum 25 is rotated with a nickel 29 in the compartment 26, the locking pawl 38 is released, as before, but no change is rendered. The nickel is rolled down the nickel channel 43 in the coin-directing member 41 transversely of the top of the tube 48. The bottom of the channel 43 extends inwardly of the tube to a position intermediate the axial center of the drum and the adjacent side thereof, so that the nickel must pass vertical alignment with the center of the drum before dropping into the slot 52. This precludes jamming of the nickel on a stack of nickels confined by the tube and obviates a source of considerable maintenance expense and inconvenience. As the nickel descends in the slot it strikes the leg 63 of the spring 61 and is diverted thereby in a reverse path of movement into the tube 48 through the slot 55.

Nickels thus delivered into the tube remain there in stacked relation for use by the change delivery slide mechanism 34, as needed. When the tube is nearly filled, successive nickels roll down the channel 43, drop through the slot 52 onto the top of the stack of nickels, and roll therefrom onto the leg 63 of the spring, and thence down the extension 49.

When the pin 31 is removed and the change-making mechanism adapted for reception of a pair of transient nickels 29 and 30 in the compartment 26, the path of movement of the first nickel 30 is as described. The following nickel 29 is inclined to follow the same path of movement but with this difference. If the drum 25 is rotated at a speed causing the following nickel 29 closely to engage the preceding nickel 30, the following nickel is frequently diverted by engagement with the preceding nickel 30 and/or the leg 63 of the spring so that it descends the extension 49 even though the tube 48 may not be entirely filled.

It will be apparent that the spacing of the leg 63 and the bottom of the slot 55 from the drum 25 is such that a single nickel cannot be jammed therebetween. When two transient nickels are utilized, and the speed of the drum rotation is such that the two nickels are diametrically aligned between a point of drum engagement and the leg 63 of the spring, as shown in Fig. 4, the spring flexes so that any tendency to jam is obviated and the first nickel descends into the coin drum in the usual manner, or rolls over the leg of the spring as the tube 48 is substantially filled, and down the extension 49. The following nickel similarly either goes into the tube 48 or descends the extension 49.

The present invention has eliminated the described difficulties in coin-change-making mechanisms and other coin handling devices. The modifications and additions to the structure of the parent coin changer are simple and inexpensive but fully effective.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent devices and apparatus.

Having described our invention, what we claim as new and desire to secure by Letters Patent is:

1. In a device of the character described, the combination of a hollow cylindrical coin tube of substantially uniform diameter mounted in a substantially erect position and having a slot

formed longitudinally thereof downwardly from its upper end, a coin directing member mounted on the upper end of the tube having an elongated coin-directing channel therein extended diametrically transversely of the tube and having a slot through the bottom of the channel from a position inwardly adjacent to the side of the coin tube opposite to the tube slot diametrically transversely of the tube aligned with the tube slot and outwardly extended therefrom, and resilient means mounted across the slot in the coin-directing member in spaced relation to the coin tube, elevationally spaced from the bottom of the tube slot a distance less than the diameter of the tube and spaced from the end of the slot in the directing member that is inwardly adjacent to the side of the tube a distance greater than the diameter of the tube.

2. In a device of the character described the combination of an elongated coin-directing member having a substantially horizontal portion, a coin tube mounted in a substantially erect position below the horizontal portion of the coin directing member, the coin directing member being longitudinally slotted diametrically of the tube from a position inwardly from a side of the tube transversely of the tube and outwardly from the opposite side of the tube, the tube being vertically slotted downwardly from the upper end thereof in alignment with the slot in the coin directing member and at the side of the tube from which the slot in the directing means is outwardly extended, and resilient means mounted transversely of the slot in the directing means in spaced relation to the bottom of the slot in the tube and in somewhat greater spaced relation to the end of the slot spaced inwardly from the side of the tube.

3. In a device of the character described, the combination of a hollow cylindrical coin tube of substantially uniform diameter mounted in a substantially erect position and having a slot formed longitudinally thereof downwardly from its upper end a distance less than the diameter of the tube, and a relatively shorter slot formed downwardly from the upper end of the tube diametrically opposite to the longer slot, a coin directing member having an elongated upwardly disposed channel therein and a downwardly directed boss mounted transversely on the upper end of the tube with the boss in fitted engagement with the shorter tube slot and with the channel transversely extended diametrically across the tube, said coin-directing member having a slot longitudinally of the channel from a position inwardly adjacent to the side of the tube having the shorter slot transversely of the tube in alignment with the longer tube slot and extended outwardly and downwardly from the side of the tube having the longer slot, and a resilient spring having a leg extended transversely of the slot in the coin-directing member below the channel in spaced relation to the tube, elevationally spaced from the bottom of the longer slot in the tube a distance less than the diameter of the tube and spaced horizontally and downwardly from the end of the slot in the coin-directing member inwardly adjacent to the side of the tube a distance approximating but greater than the diameter of the tube.

4. In a coin-handling device the combination of an elongated coin-directing member having a longitudinal coin directing channel, a substantially cylindrical coin tube of substantially uniform diameter mounted in a substantially erect position vertically aligned below the coin-direct-

10 ing member intermediate apposite ends thereof, the channel of the coin-directing member being diametrically transversely disposed to the coin tube and having a slot therein from a position inwardly adjacent to a side of the tube extended diametrically transversely of the tube and outwardly from the opposite side thereof, the tube having a slot downwardly from the upper edge thereof in alignment with the slot in the coin-directing member at the side of the tube from which the slot in the coin detecting member outwardly extends and a resilient spring mounted below the slot in the coin-directing member in spaced relation to the tube at the side thereof from which the slot in the coin-directing member extends, said spring being spaced from the end of the slot in the coin-directing member inwardly adjacent to a side of the tube a distance greater than the diameter of the tube.

20 5. In a device of the character described, the combination of a hollow cylindrical coin tube mounted in a substantially erect position and having an open upper end, a coin directing member mounted above the coin tube and extended transversely thereacross having an elongated slot therein from a position inwardly adjacent to a side of the tube transversely of the tube and outwardly from the opposite side thereof, the tube being vertically slotted downwardly from the upper end thereof in alignment with the slot in the coin directing member and at the side of the tube from which the slot in the coin directing member is extended, and resilient means mounted transversely beneath the slot in the coin directing member in spaced relation to the coin tube against which coins directed individually along the coin directing member transversely of the tube toward the resilient means are bounced for reverse movement to the tube through the slots and over which coins pass when the tube is substantially full of coins.

40 6. In a device of the character described, the combination of a hollow cylindrical coin tube mounted in a substantially erect position and having an open upper end, a coin directing member mounted above the coin tube and extended transversely thereacross having an elongated slot therein from a position inwardly adjacent to a side of the tube transversely of the tube and outwardly from the opposite side thereof, the tube being vertically slotted downwardly from the upper end thereof in alignment with the slot in the coin directing member and at the side of the tube from which the slot in the coin directing member is extended, and a spring mounted 45 beneath the coin directing member having a resilient leg extended transversely of the slot in said member a distance from the end of said slot inwardly adjacent to a side of the tube a distance approximating the diameter of the tube, at an elevation intermediate the coin directing member and the bottom of the slot in the tube, and spaced from the bottom of the slot in the tube a distance less than the diameter of the tube.
